LIGHT ADAPTER FOR SEWING MACHINE MOTORS

Solomon Redlich, New York, N. Y., assignor to Consolidated Sewing Machine & Supply Co., Inc., New York, N. Y., a corporation of New York

Application June 3, 1950, Serial No. 10,338

Term of patent 14 years

(Cl. D48—20)

To all whom it may concern:

Be it known that I, Solomon Redlich, a citizen of the United States, residing at New York, in the county and State of New York, have invented a new, original, and ornamental Design for a Light Adapter for Sewing Machine Motors, of which the following is a specification, reference being had to the accompanying drawing, forming part thereof.

Fig. 1 is a side elevation of a light adapter for sewing machine motors embodying my new design;

Fig. 2 is an enlarged front elevation thereof; Fig. 3 is a rear elevation of the same;

Fig. 4 is a top plan view, and Fig. 5 is a perspective view thereof.

Fig. 6 is a vertical sectional view as taken on substantially the plane of line 6—6 of Fig. 3.

The dotted lines shown in the drawing are for illustrative purposes only.

I claim:

The ornamental design for a light adapter for sewing machine motors, substantially as shown and described.

SOLOMON REDLICH.
